COMBINED CLOCK AND RADIO

Richard W. Lee, Evanston, and Oswald J. Mazzetta, Jr.,
Palatine, Ill., assignors to Motorola, Inc., Franklin
Park, Ill., a corporation of Illinois

Filed Jan. 15, 1964, Ser. No. 78,205

Term of patent 14 years

(Cl. D42—7)

FIG. 1 is a front perspective view of a combined clock and radio, showing our new design;

FIG. 2 is a similar view thereof, but showing the radio detached from the clock; and

FIG. 3 is a rear perspective view of the design as seen in FIG. 1.

The bottom and left side of the combined clock and radio, and the bottom, left side, and rear of the radio per se, not shown, are substantially plain and unornamented.

The essential features of our design are shown in full lines in the drawings.

We claim:

The ornamental design for a combined clock and radio, as shown and described.
